H. F. MORSE.
AIR CURRENT PRODUCING MEANS.
APPLICATION FILED SEPT. 28, 1917.

1,334,781.

Patented Mar. 23, 1920.

Inventor:
Harold F. Morse,
by *Albert Davis*
His Attorney.

UNITED STATES PATENT OFFICE.

HAROLD F. MORSE, OF PITTSFIELD, MASSACHUSETTS, ASSIGNOR TO GENERAL ELECTRIC COMPANY, A CORPORATION OF NEW YORK.

AIR-CURRENT-PRODUCING MEANS.

1,334,781.

Specification of Letters Patent. Patented Mar. 23, 1920.

Application filed September 28, 1917. Serial No. 193,825.

To all whom it may concern:

Be it known that I, HAROLD F. MORSE, a citizen of the United States, residing at Pittsfield, county of Berkshire, in the State 5 of Massachusetts, have invented certain new and useful Improvements in Air-Current-Producing Means, of which the following is a specification.

The present invention relates to air current producing means in which rotary fans are arranged to continually change the directions of the air currents produced.

More specifically my invention relates to an improved arrangement for mounting a 15 plurality of constantly driven fans to turn or gyrate about a central support.

One of the objects of this invention is to produce an arrangement of fans, preferably a pair of fans, with as few parts as 20 is compatible with utility and durability so as to turn or revolve about the support at a uniform speed.

Another object is to provide means for readily adjusting the speed of revolution 25 about the supporting member. A further object of this invention is to provide a positive drive for turning the fans about the support independent of friction and air thrust on the fans.

30 A still further object is to provide a driving means that will compensate for any wear and tear or unevenness of the driving means.

Further objects of my invention will appear from the following detailed description 35 when taken in connection with the accompanying drawing in which Figure 1 is a side elevation of a pair of fans mounted in accordance with my invention, while Fig. 2 40 is a vertical section taken in the plane of the paper through the device shown in Fig. 1, parts being broken away.

In the drawings, F and F' denote electric 45 motors having fans f and f' respectively and mounted on the frame C arranged to revolve about the pendent support D.

The fan motors may be rigidly secured to the frame C or they may be pivotally secured thereto which latter arrangement enables 50 the direction of reaction of the air current to be adjusted as desired.

In order to provide a positive drive for turning the fan motors F and F' and their supporting frame C about support D, the 55 fan motor F is arranged to drive a friction

disk, such as shown at 5 bearing against a coöperating friction member or washer 6 which is non-rotatably secured to the support D in a manner hereinafter more fully described.

The motor shaft 7 to which the fan is secured is geared down to the slow speed shaft 8 of the disk 5 by means of worms 9 and worm gears 10. The motor frame F has at its rear end a cylindrical sleeve extension entering the bore of an arm of the supporting frame C and adjustably secured thereto as by a set screw as shown in Fig. 2. Such an arrangement permits the motor to be turned in a plane at right angles to 70 the shaft 8 without interfering with the operation thereof.

The shaft 8 is provided with suitable anti-friction thrust bearing as shown at 11 and is flexibly connected to the disk 5 as shown 75 by having its inner end enter the split hub 12 of the disk 5 and a pin 13 in the shaft coöperating with the slot 14 in the hub. The disk 5 has one or more idlers 15 coöperating with the upper edge and is arranged to be held in resilient engagement with the friction washer 6 by means of the spring 16 encircling the hub and reacting through the thrust bearing 11 against a portion of the frame C.

The frame C is supported to turn about the central support D on a single antifriction bearing as shown at 20. The support D carries suitable contact rings 21 and 22, insulated therefrom for the electrical connections between the motors F and F' and the feed wires.

The friction washer 6 is made of leather, fiber or other suitable material having a high coefficient of friction and is non-rotatably but adjustably secured to the support D. The washer is clamped or otherwise rigidly secured to the flanged end 23 of the inner sleeve 24 which is in screw threaded engagement with the outer sleeve 25. The inner sleeve 24 has the screw spline 26 coöperating with the longitudinal slot 27 in the support D while the outer sleeve 25 has the screw spline 28 engaging with an annular groove cut in the collar 29 which is rigidly 105 secured to the lower end of the support D. The outer sleeve 25 can thus be freely rotated to transmit axial movement along support D to the inner sleeve 24 and thus adjust the friction washer 6 radially across the 110

face of the disk 5, the upper limit of travel being the center of the disk.

A spider 30 may be provided on the frame C to prevent undue oscillation in a vertical 5 plane of the frame C on its bearing 20.

The support D is also provided with a switch S on its lower end to control the motor circuits.

While I have shown and described a particular embodiment of my invention, which is at present the best means known to me for carrying the same into effect, I would have it understood that this is merely illustrative and that I do not mean to be limited to the precise details herein disclosed nor in the choice of mechanical equivalents except as defined in my claims hereunto annexed.

What I claim as new and desire to secure by Letters Patent of the United States is:

- 20 1. The combination with a support, of a frame rotatably mounted thereon, an electric fan carried by said frame, a driving shaft in said frame geared to the fan shaft, a disk yieldingly mounted thereon, a sleeve arranged to be movable axially on said support, a friction washer secured to said sleeve so as to be in engagement with said disk, and means for adjusting said sleeve to a desired position with respect to said disk.
- 25 2. The combination with a support, of a frame rotatably mounted thereon, an electric fan carried by said frame, a driving shaft in said frame geared to the fan shaft, a disk yieldingly mounted thereon, an inner sleeve arranged to be movable axially of said support, a friction washer secured thereto and adapted to engage with said disk, and an outer sleeve in screw threaded engagement with said inner sleeve and arranged to
- 30 35 40 adjust said sleeve relative to the face of said disk.

3. The combination of a support, of a

frame rotatably mounted thereon, an electric motor fan carried by said frame, a driving shaft in said frame geared to said motor 45 fan, a friction disk mounted on said shaft, an outer sleeve mounted on a step bearing carried by said support, an inner sleeve feathered to said support and having threaded engagement with said outer sleeve, and a 50 friction washer attached to said inner sleeve and adapted to engage said friction disk.

4. The combination of a support, a frame mounted thereon and having a tubular arm, an electric motor having a swiveled connection with said tubular arm, a drive shaft journaled coaxially of said tubular arm and geared to said motor fan, and frictional drive connection between said drive shaft and said support. 60

5. The combination with a support, of an electric motor driven fan, a frame for carrying said fan, a single bearing for rotatively mounting said frame on said support, a friction member adjustably but non-rotatably 65 secured to said support within said frame, a disk resiliently engaging therewith, and driving connections for said disk in said frame geared to said motor.

6. The combination with a support, of an 70 electric motor driven fan, a frame for carrying said fan, a single bearing for rotatively mounting said frame on said support, a sleeve in said frame having axial movement along said support, a friction washer secured to said sleeve, a disk resiliently engaging with said washer, driving connections for said disk in said frame geared to 75 said motor, and means for adjusting said sleeve to a desired position with respect to 80 said disk.

In witness whereof, I have hereunto set my hand this 26th day of September, 1917.

HAROLD F. MORSE.
